[57] CLAIM

The ornamental design for a head dress cap, as shown and described.

DESCRIPTION

FIG. 1 is a plan view of a head dress cap laid flat showing my new design;

FIG. 2 is a top view thereof;

FIG. 3 is a left side view thereof;

FIG. 4 is a right side view thereof;

FIG. 5 is a bottom view thereof;

FIG. 6 is a plan view of a head dress cap laid flat showing the underside of my new design;

FIG. 7 is a top view of a head dress cap showing my new design as it would appear in use;

FIG. 8 is a front elevational view thereof;

FIG. 9 is a left side elevational view thereof;

FIG. 10 is a rear elevational view thereof; and,

FIG. 11 is a right side elevational view thereof.
